UNITED STATES PATENT OFFICE.

GEORGE P. BOSWORTH, OF CENTRAL FALLS, RHODE ISLAND, ASSIGNOR TO HEMPHILL MANUFACTURING CO., A CORPORATION OF RHODE ISLAND.

KNITTING-MACHINE.

1,209,257.

Specification of Letters Patent. Patented Dec. 19, 1916.

Original application filed June 29, 1915, Serial No. 37,022. Divided and this application filed May 5, 1916.
Serial No. 95,642.

To all whom it may concern:

Be it known that I, GEORGE P. BOSWORTH, a citizen of the United States, and resident of Central Falls, Rhode Island, have invented certain new and useful Improvements in Knitting-Machines, of which the following is a specification.

The present specification is a division of that forming a part of application for Letters Patent of the United States, Serial Number 37,022, filed June 29, 1915, and it concerns features relating to the presser means for spring beard needle knitting machines.

15 The invention consists in the features and combination and arrangement of parts hereinafter described and particularly pointed out in the appended claims.

In the drawings: Figure 1 is a sectional view of part of a needle cylinder showing a part of my improvements. Fig. 2 is a detail view of a needle presser, web holder, and their beds, and a part of the needle cylinder, the needle being pressed; Fig. 3 is a view like Fig. 2 with the web holder partly retracted and the needle also partly retracted, the new loop length being measured off over the top of the web holder. The presser is also retracted in this view. Fig. 4 is a view like Figs. 2 and 3 with the web holder retracted and the new loop drawn into the fabric; Fig. 5 is a view of part of the needle bed and web holder bed in section, and the ring which supports the pressers, illustrated as having been removed from its place between the cylinder and web holder bed, some of the pressers being shown in place in the said ring. Fig. 6 is a perspective view in section of a portion of the web holder bed; Fig. 7 is a perspective view in section of part of the presser carrying ring; Fig. 7^a is a detail sectional view of the said ring. Fig. 8 is a plan view of the knitting head with parts broken away.

45 In the drawings, 1 indicates the needle cylinder grooved externally, and having fixed thereto to rotate therewith a bed 2 for the pressers 3 and for web holders 4. The web holders slide radially and are operated by the cam 4^a which, as in the well known Banner machine, is substantially fixed in relation to the needle cylinder, having only a limited rotary or shifting movement to accord with the shifting of the point at

which the stitches are formed in heel and toe work, said cam being held after this limited shifting movement has taken place by the stops 5 coming against a fixed part of the frame 6, Fig. 8. The web holder bed 2 and presser support or cage 8 rotate with the needle cylinder, the web holder bed being fixed thereto by screws as 9.

The pressers 3 are mounted to have pivotal movement in a direction radially of the needle cylinder, and in carrying out this part of my invention I provide a fulcrum ring or cage 8 mentioned above, in which the said pressers are mounted and which affords means for securing accurate movements of the pressers and which presents other advantages as will be hereinafter noted.

The pressers are formed with depending stem portions and upper head portions 3^a, the latter extending inwardly from the stem portions and presenting proper edge faces 75 to receive and press the needle beards. The head portions of the pressers are beveled at top and bottom to prevent the beards from striking a surface at right angles to their line of movement, which would cause breakage of the beards and preferably the upper inclined face, and the inner faces of the pressers are grooved as indicated in dotted lines at 3^a to better control the beards, though the invention is not limited in this respect. The pressers are also shouldered at 3^b, leaving the back of the head in proper relation to be engaged by the presser cam 10 adjustably secured at 11 to the relatively fixed cam ring 4^a above mentioned. The bed for the web holders is recessed at 12 to receive the cage 8, which carries the series of pressers and furnishes the fulcrum therefore, said cage resting on the ledge 12' of the bed at the bottom of the recess. The cage 95 is of special formation and is adapted to carry as a body, the whole series of pressers so that these pressers can be assembled in the cage while the same is apart from its seat in the bed 2, and then it, together with the whole series of pressers mounted thereon, can be inserted into the recess so that the whole series of pressers are made to assume proper position in relation to the needles and web holders, or the whole series of pressers can be removed as one body by taking the cage out from the recess in the bed, and in placing it or removing it, it is only

- necessary to slip it down into position in the recess or lift it out therefrom. This cage consists of a ring having a solid or intact portion and a slotted portion 8^a in the slots 5 of which the pressers 3 are held by a spring band 3^c surrounding the cage and fitting in notches of the pressers near their lower portions, the cage along its slotted wall being grooved as at 8' to receive said spring band.
- 10 The slotted portion of the cage extends up above the solid ring portion and affords lateral support for the pressers and guidance at the upper portions of their stems. The upper edge of the solid ring portion affords 15 an edge 8^c which serves as a fulcrum point on which the inner face of the stem of the presser bears and about which it turns when operated in one direction by the presser cam 10, i. e., inwardly for pressing or outwardly 20 under the action of the spring band. When the presser is in retracted position shown in Figs. 1, 3, 4, and 5, the inner edge of the stem bears on the outer face of the intact ring or body portion 8 of the cage, being 25 held in this position by the spring band 3^c. The stem of the presser tapers downwardly, and there is sufficient space between its outer edge and the inner wall of the recess to allow this stem to move outwardly when the 30 head portion of the presser is moved inwardly by the cam. The recess is of proper size also to accommodate the spring band.
- 35 The cage needs no means for holding it in position, it simply resting on the ledge by its own weight and frictional contact with the wall of the recess in the bed 2, all pressures being downward. Of course in lifting the cage out or placing it in, the cam ring 4^a would first have to be removed and the 40 web holders would also be removed. The pressers are held against circumferential displacement by web holders with which they are interspaced. The needles, however, would not be disturbed. The pressers as a 45 series can be lifted out and shifted to occupy different positions circumferentially in respect to the needles.
- 50 The web holders slide in radial grooves in the bed 2, and in grooves in the ring 13 held on top of the needle cylinder. Any presser may be removed and replaced without disturbing the cage, this being done by simply exerting pressure upwardly on the desired 55 presser by a pair of pliers grasping the head portion, the spring band yielding for this purpose, or any presser may be thrust down into position individually, its lower end being beveled and the spring band yielding for this action.
- 60 *Control of pressers.*—I have provided a presser cam mechanism which will be automatically adjustable to set the presser cams in and out at proper times. When they are out of work the presser cams are retracted 65 or moved outwardly away from the circle of

pressers, and in this position the yarn, as it shifts from one side of the yarn finger to the other in heel and toe work, will not be caught by the presser, and thus interfere with the proper taking up of the yarn. The presser 70 cams are moved in and out in alternation. Referring to Fig. 8 the presser cam 10 at the left is in its innermost position ready to perform its function of operating the pressers inwardly, and the circle of pressers is indicated at 3. The presser cam at the right is in its outermost position. The direction of rotation of the needle circle is indicated by the arrow y. Now, when the direction of rotation is reversed, the cam ring upon 75 which the presser cams are mounted is moved for a limited distance in the direction opposite to the arrow, and until the stop 5 (lower one) strikes against the fixed post 6 to which the arm 17 supporting the yarn feed fingers 80 m, m', etc., are pivoted. This oscillation of the cam ring is usual in the Banner machine to properly position or get the lead of the web holder cam in relation to the stitch point. As 85 soon as this reverse movement of the cam ring begins to take place, the presser cams 90 10 at the left begin to move outwardly due to the spring band exerting its force through the pressers, and due to centrifugal force, and due also to the fact that the controlling 95 lever 18 of the presser cam moves away from the surface of the bracket 17 or other part with which it contacted to move it to operative position. Therefore this presser cam will be at once retracted and will be out of 100 the way of the strand of the yarn at z extending from the fabric to the central yarn finger m. At the same time the lever of the right hand presser cam will be brought against the arm 17^a, and this presser cam 105 will be moved inwardly to operative position to work against the pivoted pressers. From this arrangement also it will be seen that when the bracket 17 is lifted for any 110 reason, and the yarn is withdrawn from work, both the presser cams will be free to move outwardly under the action of the spring band acting through the pressers, and because of this there will be no danger of the work being pressed off from the needles 115 should the machine be turned when the yarn finger bracket is lifted.

What I claim is:—

1. In combination in a circular spring needle knitting machine, spring beard needles, 120 pressers one for each needle, a ring or cage upon which said pressers are pivotally mounted, and a support for said cage holding the same freely removable whereby the said pressers can be removed or replaced as 125 a series, said pressers being individually removable, substantially as described.
2. In combination in a circular spring needle knitting machine, a needle cylinder, spring beard needles, instruments working 130

- between the needles radially of the cylinder, a bed for said instruments, pressers for the needle beards, one for each needle, and a cage or ring upon which the pressers are pivoted, said ring being removably carried by the said bed to permit the pressers to be moved as one body, substantially as described.
3. In combination a needle cylinder, spring beard needles, web holders, a bed for the web holders, supported on the needle cylinder and recessed adjacent said cylinder, said recess being defined by a lower ledge or support extending inwardly and being open at the top, individual pressers for the needles, and a cage or ring carrying said pressers and removably seated in the said recess and upon the said ledge, substantially as described.
4. In combination in a circular spring needle knitting machine, a needle cylinder, spring beard needles, instruments working between the needles, a bed surrounding the needle cylinder for said instruments to work in, individual pressers for the needles, and a cage or ring for said pressers consisting of a solid ring portion with a slotted portion exterior to said solid ring portion and extending also above the plane of the upper edge thereof, the said pressers having their stems working and guided in the slotted portion, and finding a bearing or fulerum on the upper edge of the solid ring portion, substantially as described.
5. In combination a needle cylinder, spring beard needles, a bed surrounding the needle cylinder, instruments mounted in said bed and working between the needles, individual pressers for the needle beards, and a cage or ring for the said pressers consisting of a solid ring portion, the upper edge of which forms a fulerum for the pressers, and a slotted portion to receive the stems of the pressers, and a spring band for holding the pressers to said cage or ring, said pressers and the walls of said slotted portion being notched on their outer edges to receive the said spring band, substantially as described.
6. In combination a needle cylinder, spring beard needles, a bed surrounding the needle cylinder, instruments working between the needles and supported by said bed, individual pressers for the needle beards, a cage or ring removably mounted in said bed and carrying the said pressers, said cage including a slotted portion to receive and guide the stems of the pressers, and a solid ring portion within the slotted portion forming a fulerum bearing for the pressers to rock upon, said pressers having an unbroken inner edge bearing on the plain face of said solid ring portion, substantially as described.
7. In combination in a spring needle knitting machine, a needle cylinder, spring beard needles, individual pressers for the needles, and a cam for operating the pressers, yarn feed means, a movable support for said yarn feed means, whereby said feed means may be removed from operative position, and means for controlling the position of the presser 70 cam to render the same inoperative when the yarn feed means is moved from operative position, substantially as described.
8. In combination in a circular spring needle knitting machine, a needle cylinder, 75 spring beard needles, individual pressers for the needle beards, a pair of presser cams to act alternately upon the pressers according to the direction of movement of the needle circle, and automatically operating means 80 for adjusting said presser cams respectively to and from operative position according to the direction of rotation of said needle circle, substantially as described.
9. In combination in a circular knitting 85 machine, a needle cylinder having rotary and reciprocating movements, spring beard needles, individual pressers for the needles, a pair of presser cams, web holders, a shiftable web holder cam ring with means for 90 automatically shifting the same according to the direction of rotation of the needle cylinder, and automatically operating means for moving the presser cams to and from operative position as the cam ring is shifted, 95 said presser cams being moved alternately to operative position in respect to each other, and being alternately withdrawn from operative position automatically, substantially 100 as described.
10. In combination in a circular knitting machine, a needle cylinder having rotary and reciprocating movements, spring beard needles, individual pressers for the needle beards, spring means for retracting the individual pressers from working position against the beards, presser cams movable radially to and from working position, web holders, a shifting web holder cam ring, 105 means for automatically shifting said cam ring according to the direction of rotation of the needle cylinder, yarn feed means, a movable support for said yarn feed means to move the same to and from operative position, and automatically operating means 110 controlled by the said shifting support to set the cams in operative position whereby, upon removal of the yarn feed means from operative position, the presser cams will be rendered inoperative by the retraction of 115 the pressers under their spring tension, substantially as described.
11. In combination in a circular knitting machine, a needle cylinder, spring beard needles, presser means, a support therefor, 120 yarn feed means, a support therefor movable to and from operative position independently of the presser support, said presser means being moved on its support and rendered effective or ineffective by the move- 125
- 130

ment or the yarn feed means and its support to operative or inoperative position, substantially as described.

12. In combination in a circular knitting machine, a needle cylinder, spring beard needles, presser means, yarn feed means movable to and from operative position, and including a yarn guide and a movable support therefor, said presser being set in operative position automatically by the positioning of the yarn guide in operative position, and spring means for moving said presser means to inoperative position, when the yarn guide is moved from operative position, substantially as described.

13. In combination in a stocking knitting machine, a needle cylinder, spring beard needles, web holders, a shifting web holder cam ring, a pair of presser means, mounted on said shifting cam ring, and means for setting one presser means in operative position when the cam ring shifts in one direction, and for rendering the other presser inoperative and for reversing the positions

of the presser means when the web holder 25 cam ring shifts in the other direction, substantially as described.

14. In combination in a circular knitting machine, yarn feed means, a needle cylinder, spring beard needles, web holders, a shifting web holder ring, presser cams mounted on the said cam ring one on each side of the yarn feed means, a movable support for the yarn feed means, the said presser cams being rendered effective or 30 ineffective alternately by the shifting of the cam ring and by parts on the yarn guide supports, and means for rendering both presser cams inoperative when the said yarn 35 guide support is moved to remove the yarn 40 guide from operative position, substantially as described.

In testimony whereof, I affix my signature.

GEORGE P. BOSWORTH.
